PUNCHING MACHINE

Lewis C. Pearce, Berea, Ohio, assignor to Standard Envelope Manufacturing Company, Cleveland, Ohio, a corporation of Ohio

Application April 28, 1945, Serial No. 590,935

14 Claims. (Cl. 164—21)

1

This invention relates to improvements in punching machines, more particularly machines for punching packs of blanks, such as envelope blanks, embodying means for feeding the blanks into operative relation with the punching mechanism and means for removing and transporting the punched blanks to a delivery stack.

One of the objects of the invention is the provision of means for taking from a stack of blanks uniform packs of a selected thickness such that for the particular die and blank stock being dealt with maximum production may be attained while maintaining an accurate cut.

Another object is the provision of an automatic feeding means for carrying blanks in packs into position upon the anvil of a punch press, punching the blanks, and conveying them to a delivery pile or stack.

Another object of the invention is the provision of means in a machine of the character stated for truing up the blanks of a pack after they are deposited on the anvil and preparatory to the punching operation.

Another object is the provision of means for accommodating a relatively long stack of blanks to be fed to an anvil positioned near the base of the machine, by the expedient of inclining the stack and the anvil.

A further object is the provision of means for separating a pack of blanks from the top of the feed stack, gripping the pack and moving it laterally onto the surface of the anvil, this mechanism operating preferably in an inclined plane so that the blanks when released by the gripping means will slide into engagement with locating stops on the anvil.

Another object is the provision of common means for moving the pack separating finger and stack hold-down finger into and out of operative position, and for setting and releasing the pack gripping finger.

Another object is the provision of means for vibrating an inclined cutting strip for dislodging cuttings from the anvil.

Another object is the provision of endless belt conveyor means for transporting the punched blanks to a delivery stack, combined with means for lifting each pack of blanks off the anvil into operative relation with the conveyor.

Still another object is the provision of means for automatically jogging blanks placed on the top of the delivery stack into correct position on that stack.

Other objects and features of novelty will appear as I proceed with the description of that

2

embodiment of the invention which, for the purposes of the present application, I have illustrated in the accompanying drawings, in which

Fig. 1 is a side elevational view, somewhat diagrammatic in character, of a machine embodying the invention.

Fig. 2 is a fragmental side elevational view, partly broken away, illustrating a portion of the machine on a larger scale.

Fig. 3 is an inclined plan view, partly in section on the line 3—3 of Fig. 1.

Fig. 4 is a side view of the supply stack and means for raising the same step by step.

Fig. 5 is a side view of the delivery stack and means for lowering the same step by step.

Fig. 6 is a fragmental view, partly in vertical section, taken upon a plane corresponding substantially with the line 6—6 of Fig. 3.

Fig. 7 is a view similar to that of Fig. 6 but showing a pack of blanks after having been lifted from the anvil and guided into operative relation with a continuously running conveyor, while the cutting strip is being vibrated to dislodge cuttings.

Fig. 8 is a detail view showing the vibrator operating mechanism.

Fig. 9 is a fragmental detail view illustrating the mechanism for actuating the clutch pedal of the punch press.

Fig. 10 is an elevational view, partly in section, illustrating mechanism for operating the diagonally moving pushers which true up the pack of blanks on the anvil.

Fig. 11 is a fragmental view of the same on a larger scale, the view being taken substantially on the line 11—11 of Fig. 3.

Fig. 12 is an elevational view illustrating mechanism for operating a rack which is attached to a reciprocable frame carrying the pack gripping finger which feeds the packs forwardly onto the anvil.

Fig. 13 is a fragmental view of the same on a larger scale.

Fig. 14 is a side view of a longitudinal member which contacts the free ends of two cranks that control stack hold-down fingers, a pack separating finger and the pack gripping and moving finger.

Fig. 15 is a transverse view, partly in section on the line 15—15 of Fig. 14.

Fig. 16 is a side elevational view, partly in section on line 16—16 of Fig. 3, showing the pack separating finger and its operating mechanism.

Fig. 17 is a detail sectional view, taken on the line 17—17 of Fig. 3, showing one of the stack

hold-down fingers and the separating mechanism therefor.

Fig. 18 is an elevational view, partly in section, of a portion of the conveyor means for transporting packs of blanks to the delivery stack, together with means for jogging the blanks and thereby truing them up upon the stack.

Fig. 19 is a plan view of the same, and

Fig. 20 is a detail plan view of the cam shaft of the machine.

The illustrated embodiment of the present invention is a machine for punching windows in envelope blanks, but the invention may be readily adapted to the handling of other kinds of blanks, as will be readily appreciated by those skilled in the art. The machine comprises two principal parts, a punching press and a feeding and delivery mechanism for depositing the blanks a pack at a time on the anvil of the press and removing the punched blanks, again a pack at a time, and conveying them to a delivery stack. The packs may be of whatever thickness the punch press is adapted to handle efficiently, but in all cases comprises a series of blanks. Accordingly, as hereinafter used, the term "pack" is to be construed as made up of a plurality of blanks.

In Fig. 1 the base of the punch press portion of the machine is shown at 25. The body 26 of the press is so adjusted that the punch die 27 and the anvil 28 are inclined at angles of about 45° to the horizontal. The flywheel 29 of the press is revolved continuously by a motor 30. The clutch which causes die 27 to make one complete reciprocation at a time in accordance with conventional practice is operated by a foot pedal 31. Die 27 is hollow. When it is forced through a pack of blanks, the cuttings enter the hollow die. A plunger, not shown, within the die, then ejects the cuttings. This also is conventional practice. A foot 32 partially surrounding the die and fixed to the head of the press strips the blanks from the die as the latter is retracted.

The blank feeding and delivery mechanism comprises a frame which is herein shown as made up of numerous steel bars, some of which rest upon the floor. The frame may be attached to the base 25 of the punch press, as by means of bolts 33 and 34, and is thus partially supported thereon. This frame includes on each side of the machine three inclined bars 35, 36 and 37 which are disposed at right angles to the anvil 28. The two bars 35 are bridged by a pair of connecting transverse bars 38 and 39, upon each of which a pair of brackets 40 are adjustably mounted, these brackets carrying adjustable posts 41 by means of which two inclined rods 42 are supported. These rods 42 which may be adjusted by the means described to fit blanks of different sizes, receive opposed notches of the blanks, as shown in Fig. 3, and in conjunction with the traveling platform 43 constitute supporting means for an inclined stack of blanks indicated at 44. The two sets of inclined bars 36 and 37 constitute guides for a pair of slides 45 upon which the platform 43 is mounted. To the ends of each of these slides there is connected a chain 46, these chains running over sprocket wheels 47 and 48 which are fixed to shafts 49 and 50 mounted in or upon the frame bars 36.

51 is the cam shaft of the machine, which is shown in detail in Fig. 20. It is driven by a chain or belt 52 from a shaft 53 in a reduction gear box 54, which gets its power from an electric motor 55 through the intermediary of pulleys 56 and 57 and a belt 58.

The feed stack 44 is adapted to be raised step by step by means of a cam 59 fixed upon shaft 51, this cam acting upon a follower 60 at the free end of an arm 61 pivoted at 62 to the frame bar 35. A link 63 is pivotally connected at its lower end with arm 61 and at its upper end it is connected by an adjustable pivot 64 with an arm 65 loosely mounted on shaft 50. A pawl 66 mounted on arm 65 actuates a ratchet wheel 67 which is fixed upon shaft 50. By this means the upper runs of chains 46 are moved upwardly a step at a time, the length of each step being dependent upon the position of adjustment of the pivot 64. The consequent upward movement of the stack is limited by a limit switch 68 having a swinging arm 69 arranged to be actuated by the upper end of one of the slides 45, and functioning to break the power circuit for motor 55.

In a plane parallel to the anvil 28 and somewhat above it there are guide tracks 70 and 71 supported by the frame of the machine. Track 70 is C-shaped in cross-section. Slidably mounted within it is a rack 72. A transverse bar 73 extends through a slot 74 in the inner side of track 70 and is welded or otherwise secured to rack 72. A brace 75 also extends through slot 74 and is secured to the rack, and at its opposite end is fastened to the bar 73. The opposite end of bar 73 extends into a guide slot 76 in track 71. The bar 73 therefore moves with rack 72. The reciprocation of the rack is accomplished by gear 77 which is fixed to one end of a stub shaft 78 that is mounted in a frame member 79 which constitutes a guide for the upper end of a rack 80 which meshes with a pinion 81 that is pinned to shaft 78. Gear 77 extends through a slot in guide track 70 in order to mesh with rack 72. Obviously, as the rack 80 moves up and down the rack 72 will reciprocate. This movement is effected by a cam 82 which engages a follower 83 that is mounted on an arm 84 pivoted at 85 to a frame member and at 86 to the lower end of rack 80. A spring 87 holds the follower against its cam.

Attached to the track 70 behind the supply stack there is a bracket 88, and a similar bracket 89 is attached to track 71 opposite bracket 88. These brackets are adjustable along tracks 70 and 71, as for example by the means illustrated in Fig. 16 where the track 70 is shown provided with a series of threaded holes 90, in any one of which a screw 91 may be mounted. Brackets 88 and 89 support a fixed transverse bar 92, and just in front of bar 92 they support trunnions 93 at the ends of an oscillatable bar 94. Bar 92 carries a pair of blocks 95 which are adjustable along the bar. Each of these blocks supports a pivot 96 upon which is mounted a hold-down finger 97 which is urged into engagement with the top of stack 44 by a compression spring 98, Fig. 17. A set screw 99 mounted in the finger engages bar 94 behind the trunnions of the latter.

On the bar 92 between the blocks 95 there is also mounted a block 100 which is provided with a groove 101 (Fig. 16) in which is slidably accommodated a pack separating finger 102 that is pointed at its forward end in order that it may readily enter between adjacent blanks at the rear edge of the stack. The rear end of this finger has an integral upward extension 103 in which is adjustably mounted a forwardly extending bolt or the like 104. A tension spring 105 attached at its forward end to the block 100 and at its rear end to a lateral projection

106 on the extension 103 tends to move the finger 102 forward and its front end downward.

Bracket 88 carries a short shaft 107 to one end of which is fixed a crank 108 with a roller 109 on its free end. Attached to the opposite end of shaft 107 there is another crank 110, the free end of which is joined by a link 111 to a crank 112 that is adjustably fixed to the adjacent trunnion 93. This adjustment may be conveniently effected in the manner illustrated in Fig. 16, where the lever 112 is shown split and is clamped to the trunnion by a set screw. Hence movement of the roller 109 downwardly will result in the tilting of bar 94 to depress the forward edge thereof. Since the finger 102 rests on the forward edge of the bar this tilting of the latter will lower the finger. At the same time the rear edge of the bar will be tilted upwardly and through the intermediacy of the screws 99 will lift the hold-down fingers 97 off the top of the stack. A spring 108' tends to raise roller 109.

The sliding bar 73 carries a pair of mounting brackets 113 in which is journaled a rock shaft 114. On one end of the latter there is fixed a crank 115 which carries at its free end a roller 116. A spring 117 tends to raise roller 116. At an intermediate position of the bar 73 there is clamped a forwardly extending pad 118 (Fig. 13) above which is mounted a slide 119 arranged to be moved by a tooth 120 on a disk 121 pinned to shaft 114. Tooth 120 extends into a slot formed in slide 119. Hence as the roller 116 moves up and down slide 119 is reciprocated. A gripper finger 122 is pivotally mounted on the under side of pad 118 and has an upwardly extending arm 123 which projects through a hole in the pad 118 and through a slot 124 in the forward end of slide 119. A tension spring 125 connects arm 123 and a projection on slide 119. When the roller 116 moves downward slide 119 moves rearwardly and rocks finger 122 upwardly into pack gripping position through the pull exerted on spring 125.

The two rollers 109 and 116 are depressed simultaneously by longitudinal bar 126 which is fastened at its ends to arms 127 and 128 that are mounted on aligned pivots 129 and 130 carried by the frame. Arm 128 projects beyond its pivot 130 and its outer end is pivotally connected with a link 131 which extends downwardly at an angle, its lower extremity being pivoted at 132 to a lever 133 (Fig. 14) which is pivoted at 134 to the frame of the machine and carries a roller follower 135 at its free end that runs upon a cam 136 keyed to cam shaft 51. As the bar 126 is moved up and down by this means the two cranks 108 and 115 are rocked simultaneously to tilt bar 94 and to close gripper finger 122, this actuation of finger 122 continuing while the bar 73 moves forward with rack 72.

A cutting strip 137 is stretched diagonally over the anvil 23 as shown in Fig. 3. This strip is moved forward between cuts a small fraction of an inch at a time by conventional means, not shown. Transverse bar 138 is supported on the frame above the anvil 23 and carries two adjustable collars 139 which support arms 140, that may be adjusted angularly. From these arms posts 141 depend and on the lower ends of these posts thin plates 142 are mounted to lie directly above the cutting strip 137. Posts 141 may be adjusted by the means indicated to fit opposed notches in envelope blanks of any one of a plurality of sizes, thereby forming stops to inter-

rupt the travel of a pack of blanks after they have been deposited on the inclined anvil.

Referring now particularly to Figs. 3, 10 and 11, 143 is an elongated pinion rotatably mounted 5 at its ends in frame members of the machine. A rack 144 on the upper end of a reciprocable bar 145 meshes with pinion 143 at one end of the latter. Bar 145 is pivoted at its lower end upon a lever 146 that is pivotally mounted on 10 frame bar 35 and carries a roller follower 147 bearing upon a cam 148 keyed or pinned to cam shaft 51. A spring 149 holds the follower against its cam.

On a transverse frame member 150 I mount a 15 pair of blocks 151 which are adjustable cross-wise of the machine. These blocks are provided with inwardly and forwardly directed diagonal guides for racks 152, the blocks being cut away on their lower sides to permit the racks to mesh 20 with pinion 143, the teeth of the rack being diagonally cut to properly fit the teeth of the pinion. Behind the blocks 150 the racks 152 have attached thereto diagonally disposed members 153 comprising pushers 154 near their forward 25 ends which, as they move forward due to the downward travel of rack 144, engage opposed notches in the blanks, push the latter into firm engagement with the posts 141 and true up the 30 pack of blanks on the anvil preparatory to the punching operation. Bars 153' are guards movable with bars 153, the purpose of which is to facilitate the travel of packs of blanks over the bars 153.

When the cut has been made, as indicated by 35 the broken line 155 in Fig. 3, the blanks are moved away from the anvil in a direction upwardly and at right angles to the surface of the anvil, partially by means of an idler roller 156 mounted in a bracket with an inclined surface 157 and partially by the upper end of a rod 158. The bracket carrying the roller is mounted on the upper end of a rod 159. The lower end of rod 158 is fixed in a bracket attached to a reciprocable member 160 carrying a follower roller 161 which bears upon a cam 162 keyed to cam shaft 51. Rod 159 is 40 slidable relative to member 160 and is biased toward a predetermined position by means of coil springs 163 and 164. The raised position of the member 160 and associated parts is illustrated 45 in Fig. 7, a pack of blanks being shown at 165.

Near the rod 158 there is a similar rod 166 which is so disposed that its upper end is adapted to engage the lower surface of the cutting strip 137. This rod 166, as shown in Fig. 8, is arranged to be 50 vibrated by a disk 167 keyed to cam shaft 51 and carrying a series of radial pins 168 which act in rapid succession upon a roller 169 attached to a bifurcated slide 170 which straddles shaft 51 and in which the lower end of rod 166 is secured.

Owing to the fact that the cutting strip is 55 stretched over the anvil, the rapid reciprocations of rod 166 vibrate the strip and effectively dislodge the cuttings, causing them to slide down the inclined surface of the anvil and drop off onto a conveyor belt 171 which is driven by a roller mounted on a shaft 172, the latter being driven by a belt 173 running over a pulley 174 on cam shaft 51.

Output shaft 53 of reduction gear box 54 carries also a sprocket wheel 175 over which runs a chain 176 that drives the sprocket wheel 177 on a shaft 178. This same shaft carries another sprocket wheel 179 over which runs a chain 180 that extends forwardly to a sprocket 181 on a shaft 182. The latter shaft carries a gear 183

which meshes with a gear 184 of the same size mounted on a shaft 185, see Fig. 2.

A conveyor belt 186 runs over a roller or pulley on shaft 185 and over a roller or pulley on a shaft 187 positioned in the frame of the machine diagonally downward and forward from shaft 185. Another conveyor belt 188 runs over a roller on shaft 182 and over a pulley or roller on another shaft 189 also positioned diagonally downward and forward and opposite the anvil 28. The lower run of belt 188 is superposed directly upon the upper run of belt 186, and these adjacent runs move in the same direction as indicated by the arrows in Fig. 2. When a pack of blanks is raised off the anvil, as shown in Fig. 7, the roller 156 and inclined surface 157 force the pack against the belt 188 and guide it into the grip of the two adjacent runs of belts 186 and 188.

After a pack of blanks reaches the upper end of the conveyor constituted by these two belts, it enters the grip of a horizontal conveyor constituted by one or more pairs of superposed belts 190 and 191. Belts 190 run over a roller on shaft 178 which is driven from the gear reduction box as previously stated, and over a roller on shaft 192 in rather close proximity to shaft 185. The upper runs of these belts 190 are supported at intervals by idler rollers 193. Belts 191 run over the previously mentioned roller on shaft 182, which is driven by chain 190, and over a roller on shaft 194 mounted at the rear end of the machine somewhat behind shaft 178. All of these conveyor belts operate continuously.

A support for a delivery stack is disposed at the rear of the machine. It comprises two vertical guide bars 195 and 196 at each side of the machine. Between each of these pairs of guide bars there is a slide 197, and these two slides support a horizontal platform 198 made up of a series of slats set on edge as indicated in Fig. 19, upon which the blanks rest. An upper shaft 199 and a lower shaft 200 carry at their opposite ends sprocket wheels over which run two chains 201, the ends of each chain being secured to the slide 197 on that side of the machine. In the operation of the machine the platform 198 is moved downwardly step by step. This action is effected by cam 202 keyed to cam shaft 51 working against a follower 203 at the lower end of a lever 204 which is pivoted at 205 to the frame bar 35. As the lever 204 swings back and forth it reciprocates a link 206 attached to an adjustable pivot 207 in an arm 208 which turns loosely upon shaft 200. Arm 208 carries a pawl 209 which engages with a ratchet 210 fixed to shaft 200. When it is desired to raise the platform 198, as at the beginning of a machine run, the pawl 209 may be disengaged manually from the ratchet 210 and the operator may then turn shaft 199 by means of hand wheel 211 in a counterclockwise direction as viewed in Fig. 1.

When the blanks are discharged at the rear end of the horizontal conveyor they strike depending stops 212 which are disposed to engage opposed notches in the blanks as indicated in Fig. 19 of the drawings, these stops being adjustable to fit blanks of different sizes. On a transverse frame bar 213 there are two blocks 214 mounted for adjustment along the bar, and in these blocks there are mounted for adjustment forwardly and backwardly two bars 215. These bars are attached to a pair of vertical rods 216 to which are also attached horizontal plates 217, the latter being connected at their rear ends to vertical strips 218 which are also connected to bars 215.

5 The horizontal portions of a pair of angular pushers 220 are mounted to slide on plates 217 from the position illustrated in Fig. 18 to a position where the vertical portions of the pushers are in line with rods 216. These pushers are adapted to engage opposed notches in the blanks, as indicated in Fig. 19, thereby working in conjunction with stops 212 to true up the blanks at the top of the vertical stack, which is indicated in Fig. 2 of the drawings at 250. Pushers 220 have forwardly extending rods 221 which project through openings in strips 218 and into tubular guides 219 carried by strips 218. Springs 222 surrounding rods 221 tend to move the pushers 220 to their rearmost position. The movement of pushers 220 forward is effected by cords or round belts 223 attached to rods 221 and running over pulleys 224 which depend from a pair of tracks 225 disposed below and parallel to the belts of the horizontal conveyor. These tracks form guides for a slideable frame made up of spaced transverse bars 226 and longitudinally extending tie bars 227. The opposite ends of the cords 223 are attached to a bracket 228 depending from the forward bar 226.

25 A link 229 is also pivoted at its forward end to bracket 228. The rear end of the link is pivotally connected with the upper end of an arm 230, the lower end of which is fixed to a rock shaft 231 mounted in the frame. One end of this shaft carries a depending arm 232 to the lower end of which is connected a reciprocable bar 233 that is bifurcated at its lower end to straddle shaft 51. It carries a follower 234 which bears upon a cam 235 that is keyed to shaft 51. A tension spring 236 holds the follower against the cam and tends to move the bracket 228 rearwardly, thereby compressing springs 222.

30 For the purpose of actuating the clutch of the punch press at the proper time in the cycle, a post 237 is mounted upon the pedal 31 and pivotally connected at its upper end with a lever 238 which is pivoted at 239 to a bracket on the frame of the machine. Lever 238 carries a roller follower 240 which is adapted to be moved downwardly from the position of Fig. 9 by a cam 241 keyed to shaft 51 working against a tension spring 242.

35 Operation.—At the beginning of a work run the platform 43 is lowered to the bottom of its path of travel by throwing pawl 66 out of action. It will then descend by gravity. Its rate of travel downwardly may be retarded by means of a hand wheel 251 attached to one end of shaft 50. Blanks are then loaded onto the platform and the rods 42 until the stack reaches to the top of the rods. Platform 198 which supports the delivery stack is raised to the top of its travel. Next the cam shaft 51 is turned by means of a hand wheel 252 on one end thereof to bring the cams into proper position for the beginning of a cycle, including the movement of rack 72 to its rearmost position and the tilting of the rear edge of bar 94 downwardly to enable springs 98 to depress hold-down fingers 97. The motors 30 and 55 are then started, causing the flywheel 29 to turn, the conveyor belts to run over their pulleys and rollers and the cam shaft to rotate.

40 The stack 44 then rises one step, after which rack 72 starts forward. This permits spring 105 to advance separator finger 102, causing the point of that finger to enter the rear edge of the stack a predetermined distance below the top thereof. Immediately thereafter the gripper finger, which is then open, moves into the space

beneath the rear edge of the pack lifted by the separator finger. Longitudinal bar 126 then moves down rocking both of the cranks 108 and 115 counterclockwise. The rear edge of bar 94 is thereby tilted upward, which relieves the pressure of hold-down fingers 97 on the stack, and the gripper finger is closed upon the pack. The rack continues to move forward with the gripper finger closed, thereby advancing the pack over the guards 153'. When the rack 72 approaches the forward end of its travel the bar 126 rises, opening the gripper finger 122 and releasing the forwardly moving pack which then slides down onto the blades 142 on the anvil 28 and over the cutting strip 137. Rack 72 then reverses its direction and continues to move backwardly until the bar 73 strikes the bolt 104 and retracts the finger 102 to clear the stack 44.

As soon as the pack is stopped by striking the posts 141, the pushers 153 move diagonally downward and inward to engage the blanks of the pack at their upper notches, which trues up the pack preparatory to the punching operation. The punching die 27 now descends to make the cut and immediately thereafter rises. At about the same time the pack is lifted off the anvil by the roller 156 and the rod 158. The cuttings are ejected from the die as previously explained, falling upon the cutting strip 137, and the blanks are stripped from the die by the foot 32. Vibration of the cutting strip through the action of disk 167 with its pins 168 then discharges the cuttings onto the anvil beyond the cutting strip, from which they slide forward onto the moving belt 171 and are conveyed thereby into a suitable receptacle placed to receive them.

The fact that in accordance with this invention uniform packs are deposited on the anvil is important. In the case of hand fed machines the operator seeks to select a pack of the maximum thickness which may be advantageously handled. He cannot judge accurately in every instance. If he errs on the conservative side his production suffers, and if he errs on the other side the die may be crowded inwardly toward the bottom of the pack with the result that the lower blanks are not accurately cut. In accordance with the present invention it is possible to determine by experiment just what thickness of pack is the optimum for a given set of conditions, and then to set the machine for that thickness, so that maximum production with uniformly excellent results is obtained.

The movement of the pack away from the anvil by the roller 156 and the rod 158 forces the rear end of the pack against the traveling belt 188, thereby imparting traction to that belt, which causes the pack to move upwardly between the two belts 188 and 186 in a direction that is generally opposite to the direction of travel of the pack onto the anvil. When the pack reaches the upper end of belt 186 it is fed into the grasp of the two sets of belts 190 and 191 and caused to travel in a horizontal direction to the rear of the machine. Here it is discharged onto the delivery stack 250 and trued up by the fixed depending posts 212 and the reciprocating pushers 228. The stack 250 is then lowered one step a distance corresponding substantially with the thickness of a pack. The cycle then repeats.

When the machine has been operated long enough so that the delivery platform 198 has reached the bottom of its travel the operator stops motor 55 and the blanks in the delivery stack are removed. Platform 43 is then lowered and

platform 198 raised, after which a new supply of blanks is added to those remaining in the feed stack. Operation of the machine may then be resumed in the manner previously described.

Variations from the described structure may be employed. Accordingly I desire it to be understood that the scope of the invention is to be regarded as defined exclusively by the appended claims rather than by the foregoing description or the accompanying illustrations.

Having thus described my invention, I claim:

1. In a machine of the character described, a support for a stack of envelope blanks, means for separating a pack of blanks of selected thickness

15 at one end of said stack and moving said pack laterally, an anvil disposed to receive said laterally removed pack, a punching die cooperating with said anvil for acting upon said pack of blanks, means for removing the punched blanks from the anvil, and means for causing endwise travel of said stack a distance corresponding to the thickness of said pack.

2. In a machine of the character described, a support for a stack of blanks, means for separating

25 a pack of blanks at one end of said stack and moving said pack laterally, an anvil disposed to receive said laterally removed pack, a punching die cooperating with said anvil for acting upon said pack of blanks, means for removing the punched blanks from the anvil, and means for causing endwise travel of said stack a distance corresponding to the thickness of said pack.

30 3. In a machine of the character described, a support for a stack of blanks, means for separating a pack of blanks at one end of said stack and moving said pack laterally, an anvil disposed to receive said laterally removed pack, a punching die cooperating with said anvil for acting upon said pack of blanks away from said anvil in a direction at right angles to the plane of its surface, means for removing the cuttings, means for removing the punched blanks, and means for causing endwise travel of said stack a distance corresponding to the thickness of said pack.

35 4. In a machine of the character described, a support for a stack of blanks, means for separating a pack of blanks at one end of said stack and moving said pack laterally, an anvil disposed to receive said laterally removed pack, a punching die cooperating with said anvil for acting upon said pack of blanks, a delivery belt conveyor running in a direction opposite to the direction of feed toward said anvil, and means for moving said pack of blanks away from said anvil into position to be taken by said conveyor.

40 5. In a machine for punching windows in envelope blanks, an anvil, a punching die reciprocable toward and away from said anvil, a pair of fixed guide posts on the anvil for engagement with a pair of opposed notches in a pack of blanks, and a pair of guide posts movable diagonally inward into engagement with another pair of opposed notches in the blanks of the pack for truing up the pack preparatory to the punching operation.

45 6. In a machine of the character described, blank punching mechanism comprising an anvil and a die reciprocable toward and away from said anvil, a drive for said punching mechanism including a single cycle clutch, mechanism for feeding blanks in packs into a predetermined position on said anvil, mechanism for removing said packs from said anvil and assembling them in a delivery pile, a cam shaft carrying cam means for actuating said feeding means and pack removing means in timed sequence, and means carried by said cam shaft for actuating said clutch to throw said punching mechanism into operation

50 70 between the feeding and blank removing operations.

75 6. In a machine of the character described, an inclined anvil, a punch reciprocable toward and away from said anvil, a cutting strip stretched

across said anvil, means for supporting a pack of blanks on said anvil above said cutting strip, means for lifting the punched blanks above said strip, and means for vibrating the strip to dislodge the cuttings.

7. In a machine of the character described, an inclined anvil, a punch reciprocable toward and away from said anvil, a cutting strip stretched across said anvil, means for supporting a pack of blanks on said anvil above said strip and overlapping both edges of said strip, reciprocable members below said anvil adapted to engage the pack of punched blanks on opposite sides of said strip and lift them out of contact with the strip, and another reciprocable member below said anvil arranged to engage the lower surface of said strip and vibrate the same for dislodging the cuttings.

8. In a machine of the character described, an inclined support for a stack of blanks, an inclined anvil disposed at right angles to said support at the upper end thereof, means for separating a pack of blanks at the upper end of said stack and moving said pack laterally in one direction onto said anvil, a punching die reciprocable toward and away from said anvil, and delivery means arranged to move said pack of punched blanks laterally in the opposite direction above said stack.

9. In a machine of the character described, means for transferring a pack of blanks from the top of a stack to an anvil disposed laterally thereof, comprising a frame reciprocable in a plane parallel to the anvil, a gripper finger mounted on said frame, a rock shaft carried by said frame, operating connections between said shaft and said gripper finger, a crank on said shaft, a longitudinal bar on which the free end of said crank runs as the said frame reciprocates, and means for moving said bar up and down to turn said rock shaft for controlling said finger in different positions of said frame.

10. In a machine of the character described, a support for a stack of blanks, an oscillatable bar disposed transversely of the machine behind said stack, a finger for separating and lifting the rear edge of a pack of blanks at the top of said stack, and a hold-down finger for engagement with the top of the stack, said bar engaging said separating finger on one side of the axis of the bar and said hold-down finger on the other side of said axis, both of said fingers being pivotally mounted behind said bar, whereby the tilting of the bar in a given direction will lower the said separating finger and raise the said hold-down finger.

11. In a machine of the character described, means for transferring a pack of envelope blanks from the top of a stack to an anvil disposed laterally thereof, comprising a frame reciprocable in a plane parallel to the surface of the anvil, a gripper finger mounted on said frame, a finger for separating and lifting the rear edge of a pack of blanks at the top of said stack, said finger

being reciprocable toward and away from the rear of the stack, means on said reciprocating frame for moving the latter finger to its rearward position, and spring means for moving it forward when the frame starts forward, said gripper finger moving beneath the rear end of said pack as the frame moves forward, and means for closing said gripper finger against the pack and holding it closed for advancing said pack onto said anvil and for releasing said gripper finger at the forward end of the frame stroke.

12. In a machine of the character described, means for transferring a pack of blanks from the top of a stack to an anvil disposed laterally thereof, comprising a frame reciprocable in a plane parallel to the anvil, a gripper finger mounted on said frame, a rock shaft carried by said reciprocable frame, operating connections between said shaft and said gripper finger, a crank on said shaft, a pack separating finger disposed behind the stack movable up and down and into and out of engagement with the stack, a crank operatively connected with said pack separating finger for moving the same up and down, means for reciprocating said pack separating finger, a longitudinal bar disposed to engage the free ends of both of said cranks, and means for moving said bar up and down.

13. In a machine of the character described, a pack delivery conveyor, comprising a pair of endless superposed belts, the adjacent runs of which travel in the same direction, the upper belt extending beyond one end of the lower belt, and means for raising a pack of blanks into position to be taken by said adjacent runs, said raising means embodying an idler roller engaging the pack therebeneath, pressing it against the upper belt and guiding it into the grip of said adjacent runs.

14. In a machine of the character described, a support for a stack of blanks, adjustable means for separating from one end of said stack a pack of blanks of a selected thickness, an anvil disposed to receive said separated pack, a punching die cooperating with said anvil for acting upon said pack of blanks, and means for removing the completed blanks from said anvil in a direction at right angles to the surface of the anvil.

LEWIS C. PEARCE.
